CARTRIDGE FOR CONTINUOUS RIBBON

William P. Bakken and Donald J. Wanek, Rochester, Minn., assignors to International Business Machines Corporation, Armonk, N.Y., a corporation of New York

Filed June 27, 1969, Ser. No. 17,914

Term of patent 14 years

Int. Cl. D18—01

U.S. Cl. D64—11

FIG. 1 is a perspective view of the cartridge for continuous ribbon showing our new design;

FIGS. 2 and 3 are respectively side views of the cartridge taken from the opposite sides;

FIG. 4 is a top plan view thereof;

FIG. 5 is a bottom plan view thereof;

FIG. 6 is a front view thereof; and

FIG. 7 is a rear view thereof.

We claim:

The ornamental design for a cartridge for continuous ribbon, as shown.
